[57] CLAIM

The original design for a surgical strap or similar article,
substantially as shown.

DESCRIPTION

FIG. 1 is a front elevational view of a surgical strap or
similar article showing my new design;
FIG. 2 is a rear elevational view thereof;
FIG. 3 is a top plan view thereof;
FIG. 4 is a bottom plan view thereof;
FIG. 5 is a view in perspective showing the surgical
strap in interconnected relation.

FIG. 1
